CHAIR

Frederick Scott, London, England, assignor to Hairlok
Limited, formerly The Hairlok Company, Limited,
Bedford, Bedfordshire, England

Filed May 14, 1971, Ser. No. 143,745

Term of patent 14 years

Int. Cl. D6—02

U.S. Cl. D6—20

FIG. 3

FIG. 4

FIG. 1 is a front perspective view of a chair embodying my new design;

FIG. 2 is a substantially side elevational view of one of the two identical sides;

FIG. 3 is a rear perspective view thereof; and

FIG. 4 is a rear elevational view thereof.

The essential features of my design reside in the shape and configuration of the chair comprising a supporting shell with inclined seat and back portions diverging at an obtuse angle from a central pillar, the back portion merging into a more upright head-rest portion, and the supporting shell being transversely concave and lined with upholstery which is nested in and conforms to the shape of the supporting shell.

I claim:

The ornamental design for a chair, as shown and described.
